UNITED STATES PATENT OFFICE.

WALTER M. BROWN, OF DAYTON, OHIO.

POPCORN-CRISP MACHINE.

1,079,591.

Specification of Letters Patent.

Patented Nov. 25, 1913.

Application filed July 31, 1912. Serial No. 712,440.

To all whom it may concern:

Be it known that I, WALTER M. BROWN, a citizen of the United States, residing at Dayton, in the county of Montgomery and State of Ohio, have invented a new and useful Improvement in Popcorn-Crisp Machines, of which the following is a specification.

This invention relates to new and useful 10 improvements in popcorn crisp machines.

The object of the invention is to provide a machine for molding popcorn, which may be driven by any of the common types of prime movers, thereby obviating the expense and difficulties involved in the use of 15 hand-operated devices.

A further object of my invention is to provide mechanism whereby, after the crisps have been formed in the molds, they 20 may be easily and effectually ejected therefrom and the machine quickly made ready for another molding operation.

With the above and other incidental objects in view, the invention consists of the 25 arrangement and construction of parts described in the following specification and specifically pointed out in the subjoined claims.

In the accompanying drawings, Figure 30 1 is a front elevation of my popcorn crisp machine. Fig. 2 is an end view thereof. And Fig. 3 is a section of the machine taken on the line *a—a* of Fig. 1.

Throughout the specification and drawings, similar reference characters denote corresponding parts.

In a detailed description of my invention, 1 designates a table which comprises legs 2, horizontal members 3 and 4, and supporting plates 5. The supporting plates 5 are mounted upon the members 4, and have longitudinal grooves formed in their inner edges to receive the tongues 6 of a surface plate 7. The surface plate 7 is rectangular 40 in form, and its length is considerably less than that of the table 1 in order that it may be moved thereon for a purpose to be hereinafter described.

Normally positioned immediately above 50 the surface plate 7 is a series of molds 8 cast in a metallic plate 9. These molds are open at both ends, and are preferably circular in cross-section. Formed in the bottom of the metallic plate 9 are two longitudinal grooves 55 into which fit guides 10 formed by the upwardly projecting edges of the supporting

plates 5. The metallic plate 9 may therefore be moved on the guides 10 the full length of the table 1.

Bolted to the table 1, and extending above the metallic plate 9, are standards 11 suitably cast from metal to support on their upper portions bearings 12 and 13 in horizontal alignment with each other. These standards 11 have curved leg portions 14 which straddle the metallic plate 9 so that the latter may have a free longitudinal movement.

Journalized in the bearing 12 is a shaft 15 upon which is loosely mounted a gear 16. The right hand hub portion 17 of the gear 70

16 is recessed for engagement with a clutch member 18 splined to the shaft 15. The clutch member 18 is provided with an annular groove 19 adapted to receive a roller carried by each of the forked ends of an arm 20 fast on a rock shaft 21. The rock shaft 21 is journaled in a bracket 22 supported on a tie bar 23 which connects and is supported by two vertically movable plates 24 to be hereinafter described. Mounted on the 80 outer end of the rock shaft 21 is a handle 24^a by means of which the clutch member 18 may be thrown into and out of engagement with the hub portion 17 of the gear 16.

The gear 16 meshes with a gear 25 fast on 85 a shaft 26 journalized in the bearing 13 supported by the standards 11, said shaft being in horizontal alignment with the shaft 15.

Also carried by the shaft 26 is a pulley 27 fast thereon, an idle or loose pulley 27^a and 90 a fly wheel 28, the pulleys 27 and 27^a being adapted to receive a belt driven by any suitable prime mover (not shown). When connected with a prime mover, the pulley 27 will rotate the shaft 26, gear 25 and gear 16, 95 and through them the shaft 15 when the handle 24^a is moved to the right to bring the clutch member 18 into engagement with the hub portion 17 of the gear 16.

Carried by each end of the shaft 15 is an 100 eccentric cam 29 which turns in a circular bore provided in a brass box 30. Carried by the middle inner portions of each of the standards 11, are two parallel guides 31 between which a longitudinal slide 32, carried by each of the vertically movable plates 24, is movable. The plates 24 are connected at their lower ends to a head 33. Depending from the head 33 is a plate 34 carrying a series of plungers 35, one for each of the molds 8. The plungers 35 are so positioned with reference to the molds 8 that they may 110

have a sliding vertical movement therein to compress the plastic material which they contain. The plate 34 has an upwardly projecting edge 36 which is recessed to receive 5 a beveled edge 37 of the head 33. The other parallel edge of the plate 34 carries set screws 38 which engage the upwardly projecting edge 39 of the said head 33. The plate 34 is thus firmly held to the head 33, 10 and by loosening the set screws 38, it may be removed therefrom to permit the plungers 35 to be thoroughly cleaned.

The plates 24 to which the head 33 is connected, have elongated openings 40 for 15 straddling the shaft 15. Connected to the upper portion of each of the plates 24, and lying on each side of the shaft 15, are transverse guide bars 41, within each set of which a cam box 30 is movable. Therefore, when 20 the cams 29 are rotated, the boxes 30 which inclose the same may have a free lateral movement within the guides 41, and engage them to impart a vertical movement to the plates 24. These plates 24, which support 25 the head 33, are guided in their vertical movement by the slides 32 carried thereby, moving between the guides 31 on the standards 11. Through the mechanism just described the cams 29, when descending, will 30 impart a downward movement to the head 33, thereby forcing the plungers 35 into the molds 8 to compress the plastic material therein, after which the plungers will be elevated above the molds by the cams 29 35 during their ascending movement. When the plungers 35 reach their normal position above the molds 8, the handle 24^a is thrown to the left to disengage the clutch member 18 and hub portion 17 of the gear 16. The 40 plungers 35 will now remain stationary for the following operation of the machine.

After the plungers 35 assume their normal position above the molds 8, the latter may be raised to bring the compressed material or 45 crisps within them into contact with the said plungers. The pressure of the plungers on the crisps as the molds continue their upward movement, will force the crisps out of the molds and permit them to drop below. 50 As the molds are raised, the surface plate 7 is moved longitudinally so as to be out of the way of the falling crisps. Adapted to engage the metallic plate 9 containing the molds 8 and move it upward, are plungers 55 42 which are vertically movable within suitable guides supported by the table 1. The actuating mechanism for the plungers 42 will be hereinafter described.

In order that the crisps may not stick to 60 the bottom of the surface plate 7 when the molds 8 are raised, the said surface plate 7 is first moved longitudinally, and when a certain point in its movement is reached the molds 8 will be raised, and from that time 65 on the movement of the molds 8 and the sur-

face plate 7 will be simultaneous. The above operation is accomplished by the following mechanism: Journaled in suitable bearings supported on each of the side members 3 of the table 1, is a rock shaft 43 upon which 70 are mounted arms 44, the free ends of which being connected by offset links 45 to the surface plate 7, to move the same longitudinally. For the purpose of rocking the shaft 43, a lever 46 is mounted on one end thereof. 75 Mounted on the side members 3, on each side of the rock shaft 43, are blocks 47 and 48 to which are pivoted toggle links 50. The toggle links 50 are pivotally connected at their free ends to toggle links 51 which are in 80 turn pivotally connected to the plungers 42. At their point of connection with each other, the toggle links 50 and 51 are connected by links 52. Carried by each of the links 52 is a lug 53. The lugs 53 are adapted to be engaged by arms 54 mounted on the shaft 43 to impart longitudinal movement to the links 52 to cause the toggle links 50 and 51 to straighten and raise the plungers 42, which in turn elevate the metallic plate 9 85 in which the molds 8 are cast.

When the lever 46 is moved to the right, the arms 44 are elevated by the shaft 43, and by means of the links 45, impart longitudinal movement to the surface plate 7. As the 95 lever 46 is further moved, the arms 54, which are also elevated by the shaft 43, come in contact with the lugs 53 and move them and the links 52 by which they are carried. This movement of the links 52 causes the 100 toggle links 50 and 51 to straighten, with the result that the plungers 42 are moved upwardly into engagement with the metallic plate 9. This upward movement is then imparted to the said plate 9, and the compressed material or crisps within the molds 8 are brought in contact with the plungers 35. As this upward movement of the molds 8 continues, the crisps are forced out of the molds by the plungers 35. In the meantime 110 the surface plate 7 has been moved out of the way of the falling crisps by the links 45, and they drop into a receptacle 55 mounted immediately below them on the table 1.

The operation of the machine is as follows: The metallic plate 9 is placed on the table 1 and the molds 8 filled with plastic popcorn. The plate 9 is then moved on the guides 10 to a position immediately under the plungers 35, so that the latter may 115 readily enter their respective molds, the surface plate 7 forming a bottom for said molds. The handle 24^a is then moved to the right to connect the power shaft 26 with the shaft 15 by means of the clutch and gears hereinbefore described. The cams 29 are then rotated by the shaft 15 to impart a downward movement to the plates 24 which in turn force the plungers 35 into engagement with the plastic popcorn within the molds, to com- 125 130

press the same. The plungers 35 are then elevated by the cams 29 during their ascending movement, until they reach their uppermost position when the handle 24^a is moved 5 to the left to disengage the clutch. The lever 46 on the rock shaft 43 is then forced upwardly to move the surface plate 7 longitudinally and elevate the molds 8 to bring the compressed material or crisps within 10 them into contact with the plungers 35. As the upward movement of the molds continues, the pressure exerted on the crisps by the plungers 35, forces them out of the molds and they drop into the receptacle 55 below. 15 I do not wish to be limited to the particular embodiments of the invention herein shown and described, and any changes or modifications may be made therein within the scope of the subjoined claims. 20 Having described my invention, I claim:

1. In a pop corn crisp machine, a plurality of vertically movable molds, a longitudinally movable surface plate forming a bottom for said molds and co-acting therewith to support the plastic material to be compressed, a series of plungers vertically movable within the molds for compressing said material, power-driven means for forcing said plungers into the molds to compress 25 the plastic material and elevating said plungers above the molds after said material is compressed, and lever-controlled mechanism for shifting the surface plate to uncover the bottom portions of the molds after 30 the plungers are in their raised position, and means actuated by said lever-controlled mechanism for elevating the molds to bring the compressed material which they contain into engagement with the plungers, after 35 said surface plate is first slightly shifted by the lever-controlled mechanism to loosen the compressed material therefrom, substantially as described. 40
2. In a popcorn crisp machine, a plurality of vertically movable molds, a longitudinally movable surface plate forming a bottom for said molds and co-acting therewith to receive the plastic material to be compressed, a series of plungers vertically 45 movable within the molds for compressing said material, power-driven means for forcing said plungers into the molds to compress the plastic material, and elevating them above the molds after said material is 50 compressed, lever-controlled mechanism for shifting the surface plate to uncover the 55

molds after the plungers are in their raised position, vertically movable plungers for elevating said molds and toggle-link mechanism for raising said plungers, said toggle-link mechanism adapted to be engaged by the lever-controlled mechanism, after the surface plate is first slightly shifted thereby, to raise the vertically movable plungers, whereby the molds are elevated to 60 bring the plastic material or crisps within them in contact with the first mentioned plungers, by which said crisps are forced out of the molds as their upward movement continues, substantially as described. 65

3. In a popcorn crisp machine, a plurality of longitudinally and vertically movable molds, a longitudinally movable surface plate forming a bottom for said molds and co-acting therewith to receive the plastic 70 popcorn to be compressed, a series of plungers vertically movable within the molds for compressing said plastic popcorn, power-driven means for forcing said plungers into the molds to compress said popcorn, and elevating them above the molds after said 75 popcorn is compressed, a shaft, a lever for rocking said shaft, arms mounted on said shaft, links connecting said arms and surface plate for shifting the latter to uncover the bottom portions of the molds after the 80 plungers are in their raised positions, vertically movable plungers for raising said molds, toggle-links for elevating said plungers, links connecting said toggle-links, a 85 lug on each of said connecting links, and arms mounted on said shaft for engaging said lugs, whereby, when the lever after first slightly shifting said surface plate to 90 loosen the crisps therefrom has reached the 95 point in its travel where the last mentioned arms engage the lugs, a further movement of said lever will cause the toggle-links to straighten, with the result that the molds will be elevated to bring the compressed 100 popcorn or crisps within them into contact with the first mentioned plungers, by which said crisps are forced out of the molds as the upward movement of the latter continues, substantially as described. 105

In testimony whereof I have hereunto set my hand this 29th day of July, 1912.

WALTER M. BROWN.
